UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

OSCILLATION-GENERATOR.

1,314,252.

Specification of Letters Patent. Patented Aug. 26, 1919.

Application filed May 13, 1915. Serial No. 27,771.

To all whom it may concern:

Be it known that I, LEE DE FOREST, a citizen of the United States, residing at New York city, county of Bronx, State of New York, have made a certain new and useful Invention in Oscillation-Generators, of which the following is a specification.

This invention relates to generators of oscillating, alternating or pulsating currents. 10 The object of the invention is to provide a generator of oscillating, alternating or pulsating electric currents which is simple and efficient.

A further object is to provide an oscillation generator of the character referred to capable of generating oscillating, alternating or pulsating electric currents of substantially uniform amplitude.

Other objects of the invention will appear 20 more fully hereinafter.

The invention consists substantially in the construction, combination, location and relative arrangement of parts all as will be more fully hereinafter set forth, as shown in the 25 accompanying drawing and finally pointed out in the appended claims.

Referring to the drawing:

The single figure is a view showing an arrangement of oscillating generator embodying my invention as applied for use in connection with radio systems.

In carrying out my invention I employ a closed, and preferably, evacuated vessel or bulb in which are located cold and hot electrodes, and I provide suitable circuit connections and current supply source to said electrodes, and where the generator is employed in connection with radio systems I associate the generator with a suitable radiating system having means connected thereto or associated therewith for altering or modifying the radiations from the system either manually, as through a telegraph key, or otherwise, as for instance, a telephone transmitter in accordance with signal code or sound waves.

Referring to the drawing I have shown the evacuated vessel or bulb U having two cold plate or wing electrodes W, in electrical connection with each other and two cold grid electrodes G in electrical connection with each other. The two cold plate or wing electrodes having a circuit connection to one side or terminal of the hot electrode 55 F, which circuit connection includes an in-

ductance coil 1 and a source of current supply indicated at B, the positive side of which is connected to the cold plate or wing electrodes W and the negative side to one terminal of the hot electrode F. In this instance 60 the circuit connection between the cold grid electrodes G, and the cold plate or wing electrodes W, includes a blocking condenser, if desired, indicated at C₃. Connected across this circuit is a variable capacity C₁, and included in said circuit is an inductance coil P, which constitutes, in the form shown, a coupling member in association with a coil S, in the antenna earth system N E the coupling being preferably a loose coupling. 70 Where the apparatus is to be used for telephoning purposes the antenna has associated therewith or includes therein a microphone transmitter M. Where the apparatus is to be used for telegraphic communication a 75 Morse telegraph key K is bridged across a portion of the inductance S. If desired, the grid and plate circuit may be inductively associated with the plate and filament circuit through inductance L as shown.

It is obvious that the current supply to the hot electrode F, or to the circuit connection of cold plate or wing electrodes W, may be controlled in any suitable or convenient manner, as, for instance, by the adjustable 80 resistance R.

By reason of the arrangements above described and by impressing an electromotive force within the space between the cold plate or wing electrode W and the hot electrode 90 from the current source B, the device U, with its electrodes and their associated circuits and circuit connections as described becomes a generator of oscillating, alternating or pulsating electric currents which are impressed upon the circuit which connects the grid and plate electrodes, the frequency of which depends upon the condition of the spatial relation of the electrode member contained therein, the value of the electromotive force impressed across the electrodes, and the amount of inductance and capacity included in or associated with the circuit connection between the cold electrodes. This frequency may be varied by 95 adjusting the capacity or inductance in said circuit connection.

By reason of the association of the oscillating circuit connecting the cold electrodes with the antenna earth system N E the 100

110

oscillating, alternating or pulsating currents in said circuit connection are impressed upon said antenna earth system, and with a natural period of oscillation in said circuit, 5 the same as that in said oscillating circuit. The emission of wave trains from the antenna earth system may be controlled in accordance with the telegraphic code through the telegraph key K which acts to short 10 circuit a portion of the inductance S. Or, if desired, the amplitude of the oscillations induced in the antenna earth system may be varied by and in accordance with sound waves falling upon the microphone transmitter M in the usual manner. It is obvious 15 that the wave length of the emitted wave trains may be altered in a manner well understood in the art.

I am unable at the present time to give a 20 wholly satisfactory explanation of the theory of the generator action of the apparatus. I have discovered, however, as hereinabove stated that a system constructed as shown and described and energized from a suitable 25 current source becomes the seat of continuous oscillations and it is my opinion that the phenomenon depends upon the inductive effect of successively applied charges or surges of potential upon the grid and plate elec- 30 trodes which charges or surges have the power to affect momentarily the conductivity of the surrounding or inter-connecting medium within the vessel in such manner that the action, when set up, is self 35 perpetuating.

It is obvious that the principles of my invention may be embodied in various arrangements and circuit connections without departure from the spirit and scope of my in- 40 vention as defined in the claims, but having now set forth the objects and nature of my invention and circuit arrangements embodying the principles thereof, what I claim as new and useful and of my own invention, 45 and desire to secure by Letters Patent, is,

1. In a system for generating oscillations, a work circuit and means for generating and transmitting the generated oscillations to

said work circuit including a device having a hot and two cold electrodes, an oscillatory 50 circuit connecting the cold electrodes, and a second circuit connecting one of said cold electrodes and said hot electrode and inductively associated with said oscillatory circuit. 55

2. In a system for generating oscillations, a work circuit and means for generating and transmitting the generated oscillations to said work circuit including a device having a hot and two cold electrodes, an oscillatory 60 circuit connecting the cold electrodes, a second circuit connecting one of said cold electrodes and said hot electrode and inductively associated with said oscillatory circuit, and a source of current included in said 65 second circuit.

3. In a system for generating oscillations, a work circuit and means for generating and transmitting the generated oscillations to said work circuit including an evacuated vessel containing filament, grid and plate elec- 70 trodes, an oscillatory circuit connecting the grid and plate electrodes, and a second circuit connecting the plate and filament elec- 75 trodes and inductively associated with said oscillatory circuit.

4. In a system for generating oscillations, a work circuit and means for generating and transmitting the generated oscillations to said work circuit including an evacuated ves- 80 sel containing filament, grid and plate elec- trodes, an oscillatory circuit connecting the grid and plate electrodes, and a second cir- 85 circuit connecting the plate and filament elec- trodes and inductively associated with said oscillatory circuit, and a source of current included in said second circuit.

In testimony whereof I have hereunto set my hand in the presence of the subscribing witnesses, on this 10th day of May A. D., 90 1915.

LEE DE FOREST.
